UNITED STATES PATENT OFFICE.

WALTER R. EIMER, OF NEW YORK, N. Y.

STENCIL-MOUNT.

1,265,632.

Specification of Letters Patent. Patented May 7, 1918.

Application filed April 20, 1917. Serial No. 163,362.

To all whom it may concern:

Be it known that I, WALTER R. EIMER, a citizen of the United States, and resident of the borough of Manhattan, in the city, 5 county, and State of New York, have invented certain new and useful Improvements in Stencil-Mounts, of which the following is a specification.

This invention relates to means for stenciling characters, figures, designs, etc., upon bottles, flasks and other articles of glass or the like, upon which etching is to be performed.

The use of stencil plates for the purpose 15 stated has hitherto been found undesirable, for the reason that even with the exercise of great care by the operator the metal plate is apt to scratch the film or coating of paraffin which has been provided upon 20 the glass surface, so that in applying the etching acid, the surface of the article may become marred through the acid attacking said surface through such scratches.

Further, no convenient means are in use 25 for holding a stencil plate in position upon an article of the character indicated, and my invention therefore comprehends a combined stencil mount and retaining means whereby the stencil plate may be held firmly 30 in position upon the object, without danger of disturbing its waxed surface, while the stencil outlines are being traced with a stylus.

Therefore my invention, in brief, consists 35 of a stencil plate, secured upon a mat or base of soft material, like chamois, which can be wrapped, contactingly, around the bottle or other article which has received a wax coating preparatory to the stenciling 40 operation, the field of this soft material being of sufficient extent so that its ends may be grasped by the operator with one hand, to hold it and the stencil plate firmly to the article. A clearance is left in the soft material. 45 behind the stencil apertures, to permit the stylus to impinge through these apertures directly upon the waxed surface.

Other features and advantages of my said invention will hereinafter appear.

50 In the drawing:—

Figure 1 is an elevation of a flask show-

ing my improved stencil mount applied thereto, and

Fig. 2 is a cross sectional view of the same.

The drawing shows a strip of soft surfaced material, *a*, such for example as chamois, fabric, or the like, whose character is such that it may be applied to a waxed or coated surface for etching purposes, 55 without scratching such surface.

The strip *a* is intended to serve as a mount for a stencil plate, as *b*, and to be suitably held in position upon a bottle, flask, or other vessel, while the outlines of figures, 65 characters or designs are marked upon a waxed or other prepared etching surface with which such vessel has been provided, in the usual manner.

In the example illustrated, the strip *a*, is 70 of sufficient length to wrap about the bottle to be etched, and to permit the ends of the strip to be grasped by the operator's hand, to thus draw said strip tightly about the bottle.

The stencil plate *b* is glued, cemented, or otherwise secured upon the outer surface of the strip *a*, which latter has a portion of its material cut away, to form a clearance *c*; exposing, at its reverse side, the stencil apertures which comprise the characters to be delineated in the wax surface for etching 80 purposes.

It will be apparent that the operator, by the use of this device, may hold the stencil 85 strip with one hand to the bottle and by the same means hold the bottle in position for convenient stenciling thereon with a stylus held in his other hand.

It is also evident that the stencil strip 90 may be otherwise secured to the bottle to thus leave the operator the freedom of both hands.

Variations may be resorted to within the spirit and scope of my invention.

I claim:

1. In a stenciling device for bottles and the like comprising a stencil plate, a backing therefor of soft material, to fit snugly against the surface prepared for etching, 100 said soft material having a clearance to expose the stencil apertures at the reverse side

of the plate, and projecting beyond the plate to afford means for holding said device in operative position, while tracing through the stencil apertures upon the etching surface.

2. In a stenciling device for bottles and the like comprising a stencil plate, a mount secured thereto, composed of a sheet of soft surfaced material of sufficient area to wrap about the bottle, whereby the ends of said sheet may be drawn together and grasped

by the operator's hand, said mount having a clearance to expose to the etching surface the stencil apertures in said plate.

Signed at the borough of Manhattan in 15
the city, county and State of New York
this 7th day of April, A. D. 1917.

WALTER R. EIMER.
